UNITED STATES PATENT OFFICE

BELLE McCONNELLOGUE, OF NEW YORK, N. Y.

DESIGN FOR A SLATE.

SPECIFICATION forming part of Design No. 27,461, dated August 3, 1897.

Application filed May 11, 1897. Serial No. 636,106. Term of patent 7 years.

To all whom it may concern:

Be it known that I, BELLE McCONNELLOGUE, a citizen of the United States, residing at New York city, in the county and State of New York, have invented and produced a new and original Design for a Slate, of which the following is a specification, reference being had to the accompanying drawing, forming a part thereof, the figure being a perspective view of a slate embodying my design.

The leading feature of my design consists of a box C, placed across a slate B, and having its bottom recessed at each end, the recesses terminating at the inner edge of the framework A and being of a depth equal to

the width of the said framework. This box is placed at the end of the slate and projects above one face or surface of the slate, and is provided with a lid D, hinged upon one side of the box C, and provided with a catch consisting of two parts E and E' for holding the lid down.

I claim—

The design for a slate, substantially as shown and described.

BELLE McCONNELLOGUE.
